(57) **CLAIM**

The ornamental design for remote control of terminal for A/V, as shown.

DESCRIPTION

FIG. 1 is a perspective view of a remote control of terminal A/V showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view thereof showing a lid in an open position on the lower portion thereof to allow access to buttons below when in use.
